BEAUTY SHOP SYMBOL

Eula L. Sharp, Rte. 2, Box 63, Luther, Okla.

Filed Jan. 8, 1959, Ser. No. 54,085

Term of patent 3½ years

(Cl. D29—1)

FIG. 1

FIG. 3

FIG. 2

I claim:

The ornamental design for a beauty shop symbol, substantially as shown.
